UNITED STATES PATENT OFFICE.

CHRISTIAN F. PAUL, OF PEEKSKILL, NEW YORK.

ELECTRICAL SNAP-SWITCH.

1,082,093.

Specification of Letters Patent. Patented Dec. 23, 1913.

Application filed October 15, 1912. Serial No. 725,840.

To all whom it may concern:

Be it known that I, CHRISTIAN F. PAUL, a citizen of the United States, residing at Peekskill, county of Westchester, and State 5 of New York, have invented certain new and useful improvements in Electrical Snap-Switches, of which the following is a full, clear, and exact description.

This invention relates to so-called "snap switches" for electric circuits, and its chief 10 object is to provide a switch which will operate with certainty under the most severe conditions of use and which can be subjected to rough usage of the most extreme character without injury to its mechanism.

To this and other ends the invention consists in the novel features of construction and combinations of elements hereinafter described, and more particularly set forth in 20 the appended claims.

One form of the invention is illustrated in the accompanying drawings, in which:

Figure 1 is a plan view of my improved snap switch, with the cover of the casing removed. Fig. 2 is a longitudinal section on line 2—2 of Fig. 1. Fig. 3 is a view partly in section on line 3—3 of Fig. 2. Fig. 4 is a detail view of the ratchet employed to permit movement of the contact buttons in one 30 direction only.

The casing 10 which incloses and protects the contact buttons and affords bearings for the shaft on which the buttons are mounted, is in the form of a flat box, rectangular in 35 plan and having a removable cover 11 secured by bolts 12. On opposite sides the box is formed with tapering extensions 13, 14 terminating in tubular necks 15, 16, through which the electric conductors are 40 led to the terminals inside. If the conductors outside the casing are inclosed in a conduit, as for example a water-proof hose-pipe, the necks 15, 16 can be inserted into the ends of the hose, thereby making a watertight joint and preventing entrance of 45 water and foreign matter. To give a firm grip on the inside of the hose the necks may be corrugated on the outside, as shown. The cover 11 also makes a hermetic joint with 50 the casing, either by means of a suitable gasket (not shown) or by accurate fitting of the contacting edges.

On the inside of the box or casing 10 at the corners thereof are four lugs or bosses 55 17, on which are mounted two transverse bars 18, 19, of insulating material, fastened

to their supporting bosses by screws 20. These bars constitute insulating supports or bridges on which are mounted the terminals of the switch. The switch terminals 21, 60 22, are mounted on the insulating bars or supports 18, 19, respectively, by means of binding bolts 23, 24, which also serve as binding posts for the inner ends of the conductors, as will be readily understood. The 65 terminals themselves are made of strips of spring sheet-metal bent in the zig-zag form shown and extend inwardly from their supporting bars. The form of terminal described is advantageous for the reason that they can 70 be made stiff enough to permit only very slight flexure vertically (as viewed in Fig. 2) and yet have ample yielding movement toward and from the insulating bars 18, 19. The maximum yielding movement relatively 75 to the bars 18, 19, with minimum flexure vertically, is obtained by giving the springs a lobe-like form at the bends, as clearly shown in Fig. 2. The terminals 21 are secured on the under side, and the terminals 80 22 on the upper side, of their respective supports, as shown in Fig. 2.

Midway between the terminals 21, 22 and parallel to the insulating terminal-supports 18, 19 is a shaft 25 journaled at one end in 85 a sleeve 26 which is itself rotatably mounted in the adjacent casing wall. On this shaft the contact element is loosely mounted, said element being composed, in the present instance, of contact buttons 27, 28, mounted 90 on a tube 25^a square in cross section, shown.

The contact buttons 27, 28, composing the contact element, are oval or elliptical in form with pointed ends, as shown, and are provided, each on one side, with contact 95 plates 29, 30; the plates being on the alternate opposite sides of the successive buttons, that is, on the left-hand sides of buttons 28 and on the right-hand sides of buttons 27 as viewed in Fig. 1. The buttons are arranged in pairs, with the contact plates connected electrically, as indicated by the short diagonal lines 31 in Fig. 1, and are separated by insulating disks 32, and at the ends of the series are the two insulating disks 33. 100 From the foregoing it will be apparent that with the buttons in the position in Figs. 1 and 2, the terminals on opposite sides of the buttons are electrically connected, and that if the buttons be turned half way around the 110 insulating faces will be brought into engagement with the terminals thus breaking the

connection. The switch illustrated is designed for a three-phase circuit and hence has three pairs of buttons and three pairs of terminals, but of course the precise number of such parts used is immaterial to the invention. As will be seen in Fig. 2, the elliptical or oval contact element in rotating with the shaft 25 has a camming action on the spring terminals; and that the rotary movement of the buttons is opposed by the terminals until such movement exceeds 90° (from the neutral position) but is aided by the terminals from that point on. Hence, to open the circuit it is only necessary to turn the buttons slightly past the "dead center", so to speak, whereupon the terminals instantly snap the buttons on to the neutral position. If the buttons are turned less than 90° the terminals tend to snap them back to the initial position. Theoretically, if the buttons are turned just to the dead center, or 90° past the neutral point, the terminals have no tendency to turn them in either direction; but with the buttons pointed, as shown, and with terminals of suitable stiffness, it is practically impossible to turn the buttons exactly to the dead center, no more or no less. Moreover, the contact plates do not cover the whole half-face of their buttons but at one end terminate short of the point, as shown in Fig. 2. Consequently if the buttons are turned far enough from the open-circuit position to bring the contact plates into engagement with the terminal-faces the points of the buttons will be past the dead center and will therefore be snapped on to the closed-circuit position; and if means are provided to permit this forward rotation to the closed-circuit position independently of the handle by which the buttons are turned it will be impossible to bring the contact plates just in engagement with the terminals and hold them there and in that way make a poor connection. For this purpose the finger-button 34 outside the casing at the end of the shaft 25 is not connected to the shaft directly but to the sleeve 26. The latter carries at its inner end a ratchet wheel 35, provided with arc-shaped slots 36, 37, extending in opposite directions 90° from the dead-center line of the buttons; the relation of the position of the slots to the contact buttons and plates being illustrated in Fig. 4, in which one of the buttons is shown in dotted lines. The disk 38 is mounted on the shaft 25 by means of a square aperture, like the contact buttons, and is provided with studs 39, 40, diametrically opposite each other and projecting into the slots 36, 37. A pawl 41, in the form of a blade spring, prevents counter-clockwise rotation of the ratchet. Referring to Fig. 4 it will now be apparent that if the finger button is turned clockwise, as indicated by the arrow, far enough to bring

the contact plate 30 into engagement ever so slightly with the coöperating terminal (thereby turning the contact button past the dead center, as previously explained) the slots will be turned at least to the positions shown in dotted lines if not farther; but the instant such positions are reached the spring terminals snap the button on to the closed-circuit position, the studs 39—40 moving in the slots without further movement of the ratchet wheel. Similarly, if the button is turned from the closed-circuit position far enough to break the connection it will have been turned past the dead center and the tension of the terminals will cause the movement to be completed. The result is that the operator cannot, even intentionally, produce a poor "make" or a poor "break", or hold the contacts in imperfect engagement with the terminals. To those familiar with the practices of ignorant, unskilful or malicious persons in operating electric switches, the great value of the feature just explained will be apparent at once.

The finger button 34 is a part of a saucer-shaped member 42, arranged in a correspondingly shaped depression in the side wall of the casing 10. On one side the depression has a recess to display the words "On" and "Off," formed on the member 42, as shown in Fig. 1. If desired, a similar finger-button can be provided at the other end of the shaft 25, as shown at 34^a, thus making the switch more convenient in use.

It will be observed that the "make" and "break" are always produced by a sliding movement of the contact plates in engagement with the terminal faces, thereby scraping and grinding the two together and insuring clean bright contact-surfaces at all times.

The switch herein specifically illustrated is merely the preferred embodiment, and it is to be understood that the invention can be embodied in other forms without departure from its proper spirit and scope as defined by the following claims.

In describing the rotatable contact element as "elliptical in cross section" I use the phrase merely as a short and convenient mode of expressing the preferred form of the element, namely, a form in which the diameter in one direction is longer than the diameter at substantially right angles to the first.

I claim:—

1. The combination of a rotatable contact element elliptical in cross-section and having axially spaced electrically connected contact-surfaces on its opposite sides; yielding terminals having contact faces bearing yieldingly on the opposite sides of the contact element to coöperate with said contact surfaces; means for connecting said terminals in an electric circuit; and means to im-

part a rotary movement to the contact element.

2. The combination of a rotatable contact element elliptical in cross-section and provided with electrically connected axially spaced contact surfaces on its opposite sides; 5 spring terminals bearing yieldingly on the opposite sides of the contact element to operate with the contact surfaces and to 10 impel the contact element when the same is turned through an appropriate angle; means for connecting the terminals in an electric circuit; and manual means to turn the contact element through said appropriate 15 angle and permit independent additional rotary movement by the impulse of the terminals.

3. The combination of a plurality of 20 yielding terminals and a rotary contact element elliptical in cross-section, coöperating to afford a rotative impulse on the said element when the same is turned through an appropriate angle; contacts on opposite 25 faces of the contact element, extending past the shorter diameter thereof from the opposite ends of the longer diameter; an actuating device to turn the rotary element in a given direction through such appropriate angle and permitting additional and independent rotation of the said element in the 30 same direction; means to prevent reverse rotation of the rotary contact element; and means for connecting the terminals in an electric circuit.

4. In a snap switch, a rotatable contact button elliptical in cross-section; and a contact extending from one end of the longer diameter of the button past the lesser diameter but terminating short of the other 40 end of the longer diameter; in combination with a yielding terminal bearing on the face of button; whereby the tension of the terminal may impel the button rotatively when the button is turned through an appropriate 45 angle.

5. In a snap switch, a rotatable contact member of substantially elliptical cross-section, in combination with a yielding terminal comprising a strip of spring metal bent to zig-zag shape and to lobe-like form at its bends and having a face bearing on the rotatable member.

6. The combination of a rotary element elliptical in cross-section and having electrically connected axially spaced contact 55 surfaces on opposite sides; yielding terminals bearing on the opposite sides of the rotary member to coöperate with the contact surfaces and comprising strips of spring metal bent to zig-zag form; means for connecting the terminals in an electric circuit; and means to turn the rotary element through an appropriate angle and permit additional and independent rotary movement thereof.

7. The combination of a pair of rotary coaxial contact elements elliptical in cross-section, each having axially spaced electrically connected contact surfaces on opposite sides; an insulating disk between the 70 contact elements; yielding terminals, one for each of said contact surfaces, on opposite sides of the contact elements and having faces to coöperate with said contact faces; means for connecting the terminals with 75 electrical conductors; and means to impart rotary movement to the contact elements.

8. In a snap switch, the combination of a rotatable contact member elliptical in cross-section and having, on its opposite sides, 80 electrically connected axially spaced contact surfaces extending from an end of the member and terminating short of the other end; yielding terminals consisting of strips of spring metal bent to zig-zag form and having faces to coöperate with the contact element on opposite sides thereof; means for connecting the terminals in an electric circuit; manual means to turn the contact element on its axis; and means to permit rotation 85 of the contact element in one direction only.

9. In a snap switch, a resilient terminal; a rotary contact element elliptical in cross-section and coöperating with the terminal, 95 whereby as the element turns on its axis the terminal is first compressed and then permitted to expand; means to turn the element on its axis and permit additional and independent rotary movement of said element by the force of the resilient terminal; means to permit rotation of said element in one direction only; and a contact surface on said element to coöperate electrically with the terminal, the contact surface terminating short of an end of the contact element, whereby to bring the contact surface into 105 electrical connection with the terminal the element must be turned past the point at which the terminal begins to expand.

10. The combination of a closed casing; parallel insulating bars inside the casing and supported thereby; yielding terminals mounted on the said bars and extending inwardly therefrom; a shaft between the bars; 115 a plurality of rotary contact buttons elliptical in cross-section and mounted on said shaft, the buttons and terminals coöperating to afford a rotative impulse on the former when they are turned through an 120 appropriate angle; and means outside the casing to turn the buttons through such angle.

11. The combination of a plurality of resilient terminals insulated from each other; 125 a rotary contact element coöperating with the terminals to receive a rotative impulse therefrom when turned through an appropriate angle; contacts thereon terminating short of one end of the longer diameter of 130

the contact element; an inclosing and supporting casing provided with openings to admit conductors; and means operable from outside the casing to rotate the contact element.

12. The combination with parallel rows of terminals arranged side by side and insulated from each other; a shaft between and parallel with said rows of terminals; and a rotary contact element elliptical in cross-section mounted on the shaft and cooperating with the terminals, the contact element having pairs of axially spaced and

electrically connected contact surfaces on its opposite sides; of an inclosing and supporting casing having tapered extensions at the sides adjacent to the rows of terminals, the extensions terminating in tubular necks; and means operable from outside the casing to rotate the contact element.

In testimony whereof I affix my signature in the presence of two subscribing witnesses.

CHRISTIAN F. PAUL.
